James Atwater
Author Patent

You dehante referred to in these Letters Patent and making part
of the same containing a description in the words of the said
James Atwater himself of his improvement in Stoves for burn-
ing hard or anthracite coal called "Atwater's Combination Stove."

To all to whom these Presents shall come Greeting --
Know ye that I James Atwater of New Haven in the County
of New Haven and State of Connecticut a citizen of said State
and of the United States have invented, made, constructed and
brought into use a new and useful improvement in Stoves for burn-
ing hard or anthracite coal which I call "Atwater's combination
stove" and which I specify and describe as follows -- The objects which
I have sought to accomplish by means of my improvement are the fol-
lowing, 1st To be able to regulate the draught of the stove and make
it stronger or weaker in degree and upward, downward, or horizontal
in direction. 2^d To be able to kindle a small quantity of anthracite
coal and continue its combustion much longer than in common stoves.

3^d To be able to economize the heat after the fire is well kindled
by turning the draught through a sufficient quantity of pipe and thus
transmitting the heat into the room. 4th To be able to clear the stove
of ashes and dust without the usual inconvenience of raising a dust
in the room, to the injury of the furniture. These objects & some others
not particularly mentioned I have accomplished by means of the
combination and arrangement of several separate parts, whether
these parts are new or old so as to form a new compound instrument
which can be sufficiently described and understood by the following
explanations of the annexed drawings -- Figure 1. is a front view of
a combination stove; a, a, represents a hollow cylinder with two doors;
b, b, and a screen C, with a glass through which the fire can be seen
In this cylinder a, a, is placed a grate for the coal constructed with
a brick extending from the bottom of the grate to the top of the cylinder
and

Aug. 23, 1833

and with one or more openings in any part of the pipe regulated with valves. Slides or stoppers which can be open and shut at pleasure. When the three openings are used in the back it will be found best to have one of these openings back of the fire to be turned and the other two near the top of the back, but as two openings will be found sufficient for ordinary purposes, and in some instances only one may be made to answer, it will generally be found best to have them as near the top of the back as they can conveniently be. The back through which the openings are made may be made from iron, brick, or stone or any other material which will sustain a high degree of heat, but iron will most commonly be found preferable for that part of the back through which the openings are made to protect the valves. Slides or stoppers are to be attached as in a hollow base and C.R. a hollow capital both of which are connected with pipes or hollow columns; f.f. & g is a draw or open constructed in the usual manner and h. is in as an ornamented top. Figure II. is a rear view of the same stone a.d. and e. represents the hollow base and capital. b.b.b. the top as seen in figure I; i.e. represents the chamber in the rear of the grate and hollow cylinder before mentioned; p.p.p. represents the rods which turn the valves which regulate the fire; h. represents the pipe which finally conducts off the smoke and heated air f.f.f.f. represents the pipes or columns through which the heated air and smoke are made to pass either directly or after they have been made to pass through the pipes f.f. or e; l represents a column which is not used as in air or smoke pipe but is used for strength and beauty. Figure III. is an interior view of the chamber represented by b. in fig. 2. m.m. represents two openings in the sides of the chamber through which the heated air and smoke pass to the pipes f. & f. 2. fig. 2. Between each of the pipes f. & f. 2. a pipe f. 3. & f. 4. is a partition on the base a.d. fig. 2. which prevents the hot air and smoke from passing on to pipes f. 3. & f. 4. and causes it to ascend on pipes f. 1. & f. 2. to the capital C.C. fig. 2. There is also a partition on the capital C.C. fig. 2. which prevents the hot air and smoke from passing on to pipes f. 5. & f. 6. fig. 2. and causes the same to ascend

Aug. 23, 1833

22

in figure 3 & 4 of 4, fig. 2, to be here den. fig. 2, where the pipe passes down and ascends in the base of 5 & 6, fig. 2, to the capital &c. fig. 2, and then runs off through the opening m. m. fig. 2, and thence to the smoke pipe n. fig. 2. The latter and smoke are made to pass on this direction through the pipes by means of two valves which are so contriv'd and placed as to close the openings o. o. in the two plates or partitions p. p. fig. 3, and when these openings are closed the escape of hot air and smoke is prevented and they can only pass through the openings m. m. fig. 3, and thence through the pipes as already described. Figure (IV) shows one of the openings m. & n. in fig. 3, and one of the valves q. when it is in the position to close the opening s. o. fig. 3; If the valves are so placed as to turn at the angle s. t. fig. 3, they will if fully turned close the openings m. m. fig. 3, whenver they will stop the openings o. o. fig. 3, and then the smoke and hot air will pass off freely through the openings o. o. fig. 2 into the smoke pipe n. fig. 2. The handle of the valve q. projects a short distance behind the chamber i. i. fig. 2. The hollow cylinder, the pipes, the base and capital, the top & the pan may be made of any suitable material, but there is none perhaps better than short iron for ordinary use. The cylinder should be lined with soap stone, a fine brick, or cast iron. But cast iron for that part of the back through which the flues or openings are made will generally be found best, and soap stone or fine brick for the rest of the lining. The size of the stone and its parts should vary according to the size of the room, hall, or chamber which is to be warmed. Figure V. is a front view of a combination stove in a form convenient to be used in a fire place or other position and can be made at less expence and to answer for all ordinary purposes as the objects sought in this invention are at fullly accomplish'd as in the combination of pipes and the base, the capital & the top shown fig. 1, and the handle, or rods of the valves q. fig. 4, on the rear of the stove as seen 1.1. fig. 2 are used as already described. The pan or cover q. and the two arms h. h. are the same as seen in fig. 1, except the upper arm is placed a little lower in fig. 5, than in fig. 1, in order to make room for the handle of the stove, valves or stoppers, one of which is to turn the

the draught through the pipes or prevent it to pass off easily, with the chimney and the slide to regulate the draught both of which have to be brought out in front above the stove. The door to in front of the grate is represented open & the front of the grate is so formed as to open and close to make it convenient to clear the grate of coal or for at pleasure, when a bellows may be used by tiring up and down (recording); or any other form may be given to the pipes or a pipe according to the taste or fancy of the manufacturer and the space to be occupied by the stove, will be had that have been nearly all of it transmitted into the room, when it may then be conducted off direct into the chimney by separate flues or brought back into any part of the chamber or smoke pipe above the slide which turns the draught as may be found most convenient. When a stove is to be set in a fire place the throat of the chimney should be carefully closed, so that no air escapes through it which does not pass through the stove or its pipes. Fig. N. 8. is a side view of the same stove on which the chamber is exhibited with one of its openings m. for the passage of hot air and smoke into the pipes. Also the handles n, n, to close the flues and their bearings o, o, and notches x, x, to keep them fast when closed and the handles y, y, to the slides or stoppers next to be mentioned are exhibited in this figure. The upper slide or stopper y is fitted to pass through the back of the cylinder and into the chamber on the rear by means of an opening a, a, which is represented in Figure N. 8. This slide is nearly large enough in width & length to close the chamber entirely when the slide is pushed back into the smoke and heated air is made to pass downward and through the chamber and through the opening at m. fig. 6. into the pipe and through the pipe into the draught which leads off the smoke. The other upper opening b, b, seen in figure 7. is a flue to which is fitted a stopper or slide to regulate the same and this stopper or slide is seen in fig. N. 8. C. C. as it appears when withdrawn from the opening in the cylinder and in the chamber. The upper slide or stopper y as seen in the drawing is placed above all the flues on the back, it may however be placed between the two upper flues

22.

flow when necessary. Figure IX is a view of a horizontal section of the chamber as seen from above when the slide door, which covers the air and smoke through the pipes is drawn out so as to leave a direct communication with the chimney or other outlet for smoke and ashes. The bottom of the chamber is constructed a little by means of the projections or, as one upon which the slide rests when it is pushed in and closes the chamber. In figure 7, there are two doors ff, ff, over the bottom of the chamber, the lower one being placed as low as possible to make it convenient to remove ashes and dust which collect at the bottom of the chamber. The upper one can be used as a flue when the other flues are all stopped, and the draught will then be turned conveniently through the bottom of the grate gg, gg, in fig 7, denotes the flue on the back of the stone opening into the chamber already described and seen in fig 6, b, b, which flues are regulated by valves and moved by the hands u, u, in fig 6 - a stand or frame for the stone to stand on and a pan for ashes & coal, to be placed near the stone in front will be found useful, they may be made from such materials & in such form & size as shall be most convenient. I claim as my invention the combination and arrangement by which the separate parts are adapted to each other and formed into one compound instrument to accomplish the four objects enumerated at the commencement of this specification which separate parts so combined are the following (viz) 1st a cylinder, prismatic or furnace tube with one or more openings in any part of the back thereof, regulated with one or more valves, slides or stoppers, which can be opened and shut at pleasure, 2nd an air and dust chamber on the rear of the back of the grate or stone into which the flues open with one or more outlets for heated air and smoke and one or more doors at the bottom below the grate to remove dust and ventilation being an object of necessary to regulate the draught. 3rd a set or collection of one or more pipes in any form but so arranged as to be connected with the air chamber for the retention and diffusion of heat through the pipes into the room. & the 4th a set of one or more valves, slides or stoppers by which the passage is made to pass through the pipes of course in

7725x

Aug. 23, 1833

directly off in the usual way). This does not claim any of the separate parts separately taken or any of the particular parts of the separate parts in this Patent as my invention, but the combination and arrangement of all the parts whether the parts are new or old to form a whole compensation instrument as aforesaid. In testimony whereof the foregoing is a true specification of my said improvement as above described. These documents are my hand and seal this 22nd day of July, 1833.
